JAMES McLAUGHLIN AND CHARLES W. JONES, OF DUNCANNON, PENNSYLVANIA, ASSIGNEES TO THEMSELVES AND WILLIAM C. KING, OF SAME PLACE.

Letters Patent No. 67,443, dated August 6, 1867.

IMPROVED RAILROAD-SWITCH.

The Schedule referred to in these Letters Patent and making part of the same.

TO ALL WHOM IT MAY CONCERN:

Be it known that we, JAMES McLAUGHLIN and CHARLES W. JONES, of Duncannon, in the county of Perry, and State of Pennsylvania, have invented a new and improved Self-Acting Railroad-Switch; and we do hereby declare that the following is a full, clear, and exact description thereof, which will enable others skilled in the art to make and use the same, reference being had to the accompanying drawing, forming part of this specification.

The drawing represents our improved self-acting elastic switch applied to a railroad main track and siding.

The invention relates to an improvement in the construction and arrangement of railroad-switches, which consists in connecting elastic rails on a main and side track in such manner that the wheels of a locomotive and car shall move the rails by springing them apart parallel with each other, and thus connect the ends of the rails on the main and side tracks, as hereinafter more particularly described.

On a main track formed of stationary rails *a a*, the switch is made by means of an elastic rail, *a'*, the free end of which abuts naturally against one of the straight stationary rails *a*, and is connected with a shifting-bar, *b*, to throw it out of line with the main-track rail *a*, and into line with the diagonal stationary rail *c* placed between the rails *a a* of the main track. The end of the elastic rail *a'* is held down upon the chair *d* by means of two cross-bars, *e e*, under which the shifting-bar *b* slides and is kept in place; and on the sides of the rail *a'* are guard-pins *n n* which allow it to move back and forth sidewise, in line with either the rail *a* on the main track or the diagonal rail *c*, as hereinafter described. The shifting-bar *b* extends under an elastic rail, *k k*, of a side track, and is pivoted to one end of a lever, *m*, which is pivoted upon a cross-tie, *x*, and bears with its other end against the side of the elastic rail *k*. This rail *k* is fastened at two points firmly by spikes *s s* on each side, while between these two points are guard-pins *t t*, on one side in the line of a curve shown in red to support the rail when pushed against them by the wheels of a locomotive or cars to operate the switch for passing off and on a siding.

It will be seen that when a locomotive is let in on the side track at the main-track switch, with the wheels on one side running on the diagonal rail *c*, the wheels on the other side of the locomotive will bear against and press the elastic rail *k* up against the guard-pins *s s* to the curved line shown in red, when the lever *m* will move the shifting-bar *b* and shift the end of the elastic rail *a'* in line with the diagonal rail *c*, as shown in red, and thus operate as a switch to guide the locomotive from the main track to the siding by its own action. After a locomotive or train has passed the elastic rails will resume their original position, and thus place the rail *a'* again in connection with the rail *a* of the main track. The switch, therefore, is always in place on the main track, except when moved by the passage of a locomotive on or off of a side track in the manner described. The elastic switch may be applied to single or double rails, and the elastic rails may be made of steel or iron, as desired.

Having thus described our invention, we claim as new, and desire to secure by Letters Patent—

An elastic self-acting railroad switch, arranged and operating substantially as herein described.

JAMES McLAUGHLIN,
CHAS. W. JONES.
